MAX JAEGER, OF MOUNT VERNON, NEW YORK, ASSIGNEE TO JAEGER ROTARY VALVE
MOTOR CO., OF MOUNT VERNON, NEW YORK, A CORPORATION OF NEW YORK.

ROTARY VALVE.

1,073,949.

Specification of Letters Patent.

Patented Sept. 9, 1913.

Application filed April 1, 1912. Serial No. 687,586.

To all whom it may concern:

Be it known that I, MAX JAEGER, a subject of the German Emperor, and a resident of Mount Vernon, in the county of Westchester and State of New York, have invented a new and Improved Rotary Valve, of which the following is a full, clear, and exact description.

This invention relates to improvements in rotary valves.

The object in view is to provide an improved valve structure designed to continuously rotate during the operation of the engine or other machinery to which it is connected, and operate with the expenditure of a minimum amount of power.

Another object of the invention is the provision of an improved valve structure formed with a head comprising an inner and an outer water-cooled member with a rotating valve sleeve structure interposed, the valve sleeve structure controlling the admission and the exhaustion of gases to and from the cylinder or cylinders through the inner member.

A still further object of the invention is to provide an improved valve structure for explosive engines, in which the controlling member is a sleeve having ports arranged therein, the sleeve being adapted to rotate about a stationary casing formed with intake and exhaust passageways having intake and exhaust openings facing toward the cylinders of the engine and adapted to be in communication therewith when the respective ports of the rotating sleeve are moved to register therewith.

A further object of the invention is the provision of an improved simplified rotary valve having a minimum number of parts, and a single rotating member connected in any suitable manner to the driving shaft of the engine, the rotary member being preferably held in place by antifriction members and protected by a film of oil interiorly and exteriorly, whereby a substantially noiseless valve will result.

In carrying out the objects of the invention, the valve may be connected with one or more cylinders as desired. The valve structure is connected directly with the heads of the respective cylinders of the engine with which it may be associated, so that the gases may be directly forced into the cylinders

and forced therefrom, thereby securing a maximum efficiency. The valve comprises a head having an outer casing and an inner casing secured together and to the cylinder or cylinders of an engine in such a manner that the water-cooling jacket of the engine is in communication with waterways in the head, whereby water entering the lowermost part of the water jacket of the engine will pass out the highest point of the head. Arranged between the inner and the outer casing of the head is a rotating valve sleeve formed with ports therein, the number of ports being regulated, of course, by the number of cylinders composing the engine. This sleeve is connected to the driving shaft of the engine in any desired manner so as to move at the desired ratio for causing a proper intake and exhaust of the gases, the ports in the valve sleeve regulating the flow of gases and the exhaust through the inner casing of the head, the inner casing of the head being provided with suitable passageways and ports for registering with the ports of the sleeve at proper times.

A practical embodiment of the invention is represented in the accompanying drawings forming a part of this specification, in which similar characters of reference indicate corresponding parts in all the views.

Figure 1 is a longitudinal vertical section through a valve embodying the invention, the same being shown applied to an engine; Fig. 2 is a section through Fig. 1 on the line 2—2, the same being shown on a slightly enlarged scale; Fig. 3 is a section through Fig. 1 on the line 3—3; Fig. 4 is a section through Fig. 1 on the line 4—4; Fig. 5 is a section through Fig. 1 on the line 5—5; Fig. 6 is a section through Fig. 1 on the line 6—6; Fig. 7 is a section through Fig. 1 on the line 7—7; Fig. 8 is a section through Fig. 1 on the line 8—8; Fig. 9 is a section through Fig. 1 on the line 9—9; Fig. 10 is a section through Fig. 1 on the line 10—10; Fig. 11 is a longitudinal horizontal section through an inner casing forming certain features of the invention, the same being taken substantially on the line 11—11 of Fig. 1; Fig. 12 is an enlarged fragmentary view showing the operating gear mechanism and part of the inner and outer casing, the same being a section on the line 12—12 of Fig. 1; Fig. 13 is a fragmentary perspective view of one end of

- the head showing an extension for receiving a locking device for preventing the shifting of certain moving parts when the valve is disassembled; Fig. 14 is a fragmentary view 5 on the line 14—14 of Fig. 1, showing the outlet water pipe leading from the inner casing, the same being shown on an enlarged scale; and Fig. 15 is a side view of the rotating valve sleeve.
- 10 In constructing an embodiment of the invention, an engine 1 of any desired kind may be used, preferably of the four-cycle type having one or more cylinders. In the drawings four cylinders have been shown 15 for the purpose of illustration though it will be evident that a greater or less number could be used. Arranged in the main casting of the engine, as a preferable structure, are a plurality of removable cylinders 5, 6, 20 7, and 8. These cylinders or sleeves are preferably provided with a high or smooth-polished surface on the interior so that the deposit of carbon will be minimized and consequently the high efficiency of the engine 25 maintained. The sleeves are also preferably slidably fitted into the main casting of the engine. In order to provide a perfectly tight joint, a gasket 4 is provided at the lower end of the sleeves. This gasket may 30 be constructed of a soft metal, as lead or Babbitt metal, or if desired may be constructed of fiber or asbestos, or other suitable material. The cylinders 5, 6, 7, and 8 are adapted to accommodate pistons 9, 10, 11, 35 and 12, respectively, these respective pistons being set in the usual way, the controlling inlet and outlet ports being correspondingly arranged so as to cause a proper action of the various parts. These cylinders are 40 rounded by a water jacket 13 opening into passageways 14 which register with the water jacket space 15 of the head 16. A suitable spark plug 17 of any desired construction is provided at any desired point in the 45 lower part of the head 16 for each of the cylinders so as to be above the extreme upward movement of the respective pistons, and near the intake opening so as to be surrounded by a new explosive mixture.
- 50 The head 16 is secured to the upper end of the main casting in any desired manner, as for instance, by bolts, and acts as the housing for the rotary valve which co-acts with the cylinders, pistons, and other parts, 55 for making a complete operative structure having a minimum amount of friction and a minimum waste of power. The head 16 is formed with an outer casing 18 and an inner casing 19, having positioned therebetween a rotary valve sleeve 20. The outer casing 18 is provided with a water receiving space or chamber 15 and is bored out to accommodate the sleeve 20. The walls of the 60 respective cylinders of the engine merge, in a certain sense, into the walls of the combustion chambers 2 which are the lower parts of the outer casing, and by reason of this fact the inner wall of the outer casing is open from points 21 to points 22. This permits a free communication between the 70 respective cylinders and the various passageways hereinafter fully described, in the inner casing whenever the respective ports 23 of the rotating valve sleeve 20 are positioned in registry with the opening between the 75 points 21 and 22.
- It will be noted that the outer casing, inner casing, and bearings are a single unit forming a single stationary head inside of which a single sleeve is located designed to 80 rotate as the engine or other machinery to which it is connected is operated. The head is made of a plurality of parts only for the convenience of working and getting the rotating sleeve in and out.
- The inner casing 19 (Figs. 1 and 11) is 85 provided with a plurality of intake ports 24, 25, 26, and 27, and a plurality of outlet ports 28, 29, 30, and 31, thus providing an inlet port and an outlet port in the inner casing 90 for each of the four cylinders. If the valve were used on an engine having only two cylinders, it will be evident that only half the number of ports described would be used. An exhaust passageway 32 is provided in 95 the inner casing 19 which extends for substantially the full length of the inner casing and is in continuous free communication with the exhaust ports in the inner casing and with the discharge opening 33 arranged 100 in the end 34. The inlet ports are continually in free communication with passageway 35, so as to distribute more evenly the gases to the respective cylinders from passageway 36 which at the end 38 merges into 105 an intake opening 39. The end 38 may be connected to a suitable supply of explosive mixture in any desired manner so that a continuous supply of explosive mixture is provided for the respective cylinders. The 110 discharge opening 33 at the opposite end of the inner casing 19 is connected to any suitable pipe or other means for directing the exhaust to a point of discharge, as for instance to a muffler. It will be evident that 115 if it is desired the discharge opening 33 could be left unconnected with any pipe so that the exhaust would be discharged directly into the atmosphere. From Fig. 11 it will be observed that between the passageway 32 and the passageway 35 and adjacent passageway 36 are arranged passageways or 120 chambers 40, 41 and 42, these chambers being designed to be supplied with a cooling fluid, as for instance water, received from the chamber 15 through a pipe 43 and an intake passageway 44. After circulating through the chambers 40, 41, and 42, the water passes out through a pipe 45 into the 125 upper part of the chamber 15 and from 130

thence out through a discharge opening 46, the water or other cooling fluid being originally inserted into the cooling jacket through a pipe 47 near the lower end of the main casting. In this way all the parts are maintained properly cooled so that the same may operate as designed, the water or other cooling fluid entering at the lowermost point and escaping at the highermost point, whereby the natural circulation of the water is maintained. In order to positively cause a flowing of the cooling fluid, a pump of any desired kind may be connected with the pipe 47.

In order to assist in the natural action of the flow of the cooling fluid, the thickness of the walls of the inner casing is varied so that the lowermost point in the water chamber in the inner casing will be at a point farthest from the point at which the water enters. This will cause the entering cool fluid to gravitate by its weight so as to move longitudinally of the casing to the end opposite the entering end and then, as the same is heated, to rise and gradually pass back to the entering end but to the upper part thereof where the discharge opening is located. Also it will be noted that the highest point in the water chamber of the inner casing opens into the discharge pipe which directs the water to the upper part of the water chamber 15. With this arrangement the water or other cooling fluid will circulate to the farther end of the inner casing and thereby effectively cool all parts of the casing.

The rotating valve sleeve 20 is formed with a port 23 for each of the intake ports and each of the exhaust ports, these ports 23 being set at any desired angle, as shown for instance in Figs. 3 to 10 inclusive, for causing the proper intake and exhaust of the gases. It will, of course, be evident that the sleeve 20 is geared or otherwise connected with the driving shaft of the engine so as to act in proper timed relationship for causing the proper opening and closing of the intake and exhaust ports. It will be observed that the inner casing 19 is held stationary and that the ports arranged therein face toward the respective cylinders of the engine so that whenever the ports 23 are in registry therewith the respective cylinders will be in free communication with either the intake or exhaust ports of the inner casing. Rigidly secured to one end of the sleeve 20 (Fig. 1), is a gear wheel 48 meshing with a gear wheel 49 (Fig. 12). These gear wheels are arranged within the end casing 50 which is removably secured to the outer casing 18. In order to provide a proper journal for the gear wheel 49, the casing 50 is extended out at 51, whereby the gear wheel 49 is caused to properly mesh with the gear wheel 48 and the operating

shaft 52 to extend in any desired direction, as for instance toward the driving shaft of the engine to which it is connected by gears or in any other desired manner. It will be evident that the sleeve 20 could be connected with the driving shaft of the engine by sprocket wheels and a chain, or by other means, whereby the sleeve 20 will operate in the proper ratio to the action of the respective pistons. In order to properly support the rotating sleeve 20 within the space between the inner and outer casings, antifriction members 53 and 54 are provided for supporting the sleeve, whereby there will be no friction between the sleeve and the inner and outer casings. In order to maintain proper lubrication and to provide for a tight valve structure continually, an oil film is provided between the inner casing and the sleeve and between the outer casing and the sleeve. The oil cups 55 connected to the outer casing have passageways 56 which extend into a longitudinal groove 57 in the outer casing whereby oil is freely distributed to the surface of the sleeve 20. During the rotation of the sleeve 20 part of the oil passes through the ports 23 and enters the longitudinal groove 58 which causes a proper distribution of the oil over the interior of the sleeve and the exterior of the inner casing thus providing an inner and outer film of oil for the sleeve so that substantially all of the friction is between the two oil films and between the antifriction members 53 and 54 and the sleeve. An anti-friction device 59 is also provided for taking care of the end thrusts of the rotating sleeve. This antifriction device is formed in the usual manner of bearing rings and balls arranged therebetween embodying the same principle as the anti-friction members 53 and 54 except that it takes up the end thrusts. A similar end thrust bearing may be provided at the opposite end of the rotating valve sleeve.

In constructing the head 16 for the purpose of assembling and dismantling the device, it is found necessary to form the outer casing with end head numbers 50 and 50', these members being held in place by suitable screws or bolts. After the device has been first assembled the end head 50' and also the end head 50 is removed when it is desired to take out the sleeve and the inner casing. In order to provide a proper registering device so that the parts may be assembled correctly, a single bolt or screw 59', larger than the remaining bolts, is provided so that the head 50 may be removed and replaced correctly. The gear wheel 48 is provided with a notch or depression 60 designed to accommodate a pin 61 slidably mounted in the head member 50. The pin 61 is provided with a shoulder 62 in engagement with a spring 63 normally under ten-

sion operating in a bore 64, whereby the pin 61 is being continually urged inward so as to be projected into the notch 60 when turned for locking. A pin 65 is fitted in the pin 61 and normally rests in a slight groove 66 in the extension 67 for holding the pin 61 in its withdrawn position, as shown in Fig. 1, whereby the gear wheel 48 and associated parts may freely rotate. When it is desired 10 to remove the head member 50 and the inner casing and associated parts, the pin 61 is rotated so that the pin 65 will fit into notches 68 formed comparatively deep, whereby the pin 61 is permitted a longitudinal movement sufficient for causing the same 15 to enter the notch 60 in the gear wheel 48, the gear wheel 48 being screw threaded or otherwise rigidly secured to the sleeve 20. The inner casing 19 is keyed at 69 to the 20 head member 50 so that when the pin 61 is engaging the notch 60, the head member may be removed, together with the sleeve and inner casing, without disturbing the adjustment of the various parts. After the 25 device has been taken apart and the sleeve and other parts removed, and it is again desired to assemble the various parts, the bolt 59' will permit the proper positioning of the head member 50 on the outer casing 30 and the pin 61 will permit the proper positioning of the sleeve 20 in regard to the inner casing without the necessity of accurate measurements and other calculations for causing the ports to properly register. It 35 will also be observed that the enlarged bolt or screw 59' will cause the head 50 to be positioned correctly when re-assembled so that the respective intake ports and exhaust ports of the inner casing will be correctly 40 positioned. When re-assembling the motor the crank shaft is turned until the two inner pistons are in their lowermost position and the two outer pistons in their highest position so as to be correctly timed when the 45 sleeve and associated parts are replaced. It will also be observed that the key 69 positively locks the inner casing stationary so that the only moving part of the valve arranged opposite the cylinders is the sleeve 50 which continually rotates as long as the engine is in operation. Suitable locking nuts 70 and 71 may be provided on the ends 34 and 38 for positively locking the inner casing against longitudinal movement. 55 In forming a device according to the present invention it will be noted that a minimum number of moving parts are provided and in fact only one principal moving part is provided, namely, the sleeve 20. Of course the necessary connecting parts are provided for causing the proper rotation of this sleeve. The remaining parts of the valve are held stationary and are thoroughly water-cooled. Also it will be noted that 60 by the construction of the rotating valve 65

sleeve, as set forth, friction is reduced to a minimum and thus the life of the valve is greatly lengthened as well as the reduction of the power necessary to operate the valve.

Having thus described my invention I claim as new and desire to secure by Letters Patent:—

1. In a rotary valve for explosive engines, an outer casing, a stationary inner casing arranged in the outer casing and spaced therefrom, said inner casing being provided with an inlet passageway extending for a part of the full length thereof and merging into branches for more easily distributing the explosive mixture, an outlet passageway 75 extending for substantially the full length of the inner casing, a port from each of said passageways for each cylinder of said engine, and a substantially centrally arranged cooling chamber, and a rotary valve sleeve 80 arranged in the space between said stationary inner casing and said outer casing, said sleeve being formed with ports registering at predetermined times with the ports in the inner casing for causing a proper intake 85 and exhaust from said cylinders.

2. In a rotary valve for explosive engines, an outer casing formed with a water jacket in communication with the water jacket in said engine, a stationary inner casing adjacent said outer casing and spaced therefrom, said inner casing being formed with a water-cooling chamber, means for connecting the bottom part of said water-cooling chamber with the water jacket of said 100 outer casing, means for connecting the upper part of said water-cooling chamber with the upper part of said water jacket of said outer casing, whereby the cooling water may circulate in a general upward direction through the water jacket of said outer casing and through the water cooling chamber of said inner casing, and a rotary valve structure arranged in the space between 105 said outer casing and said inner casing.

3. In a rotary valve for explosive engines, an outer casing formed with a longitudinal oil groove, means for supplying said oil groove with oil, a rotating sleeve arranged in said outer casing adjacent said oil groove whereby oil is distributed to the outer surface of said sleeve, said sleeve being formed with a plurality of ports, an inner casing surrounded by said sleeve formed with a plurality of ports adapted to 115 register at predetermined times with the ports of said sleeve, said inner casing being formed with a longitudinal oil groove designed to receive oil through said ports from said first mentioned oil groove, whereby said sleeve is protected by an inner and outer film of oil, and means for rotating said sleeve.

4. In a rotary valve for explosive engines, an outer casing, an inner casing formed with 120

- intake and exhaust ports and with intake and exhaust passageways, a rotary valve sleeve positioned between said casings formed with ports arranged to at predetermined times register with the ports in said inner casing, a removable head associated with said outer casing, means for rigidly securing said head to said inner casing, and an identifying member for connecting said head with said outer casing whereby the head may be always positioned in the same place upon each removal and replacing. 5
5. In a rotary valve for explosive engines, an outer casing, a stationary inner casing, a rotary valve sleeve arranged between said casings, means for rotating said valve sleeve, a removable head associated with said outer casing, means for rigidly securing said head to said inner casing, selective registering means for connecting said head and said outer casing whereby the head is always positioned correctly, and a locking structure adapted to at times engage the means for rotating said sleeve for locking the same to said head, whereby the sleeve, the head, and the inner casing are rigidly connected together, said locking means comprising a reciprocating pin adapted to engage the depression in said means for rotating said sleeve, a spring for normally tending to move said pin toward said depression, and a stop connected with said pin for normally preventing movement of said pin, said head being formed with a slot for accommodating said stop when it is desired that the pin shall engage said depression. 10
6. In a rotary valve for explosive engines, a stationary outer casing, a stationary inner casing, a rotary sleeve arranged between said inner and outer casings, means for rotating said sleeve, a removable head secured to each end of said outer casing, and a plurality of means for locking one of said heads rigidly to said inner casing and said rotary sleeve whereby said last mentioned head, the rotary sleeve, and said inner casing may be removed and replaced without dislocating any of the parts. 15
7. In a rotary valve for explosive engines, a stationary outer casing, a stationary inner casing positioned in said outer casing, but adapted to be removed therefrom, a removable head for each end of said outer casing, engaging the end of said inner casing for supporting the same, said inner casing being spaced from said outer casing, a rotating sleeve arranged in the space between the outer casing and the inner casing, means for rotating said sleeve, means for connecting one of said heads rigidly with said inner casing, an identifying locking member for connecting at will said rotating sleeve with said last mentioned head, and an identifying member arranged to engage said stationary outer casing and said last mentioned head 20 for causing the same to be properly positioned at each disassembling and re-assembling. 25
8. In a device of the character described, the combination with an explosion engine, of a rotary valve for said engine, said rotary valve being formed with a stationary outer casing, a rotary valve member arranged in said stationary outer casing formed with a plurality of ports, and a stationary inner casing formed with a plurality of ports designed to register with the ports in said rotary valve member at predetermined times, said inner casing being also formed with a water passageway therethrough for receiving a cooling fluid, said water passageway being positioned at an incline whereby the cooling fluid may enter at the lowermost point and pass out at the uppermost point. 30
9. In a device of the character described, the combination with an explosion engine formed with a plurality of cylinders, of a rotary valve structure connected to the ends of all of said cylinders, said rotary valve structure comprising a stationary outer casing, a stationary inner casing spaced from said outer casing, said stationary inner casing being formed with a plurality of inlet passageways merging into inlet ports, and a plurality of outlet passageways merging into outlet ports, and a cooling fluid receiving chamber extending in a general upwardly inclined direction in respect to the periphery of the inner casing, and a rotating valve sleeve formed with a plurality of ports positioned between said inner casing and said outer casing, the ports in said sleeve registering at predetermined times with the ports in said inner casing whereby the inlet and exhaust of the cylinders of said engine will be controlled. 35
10. In a rotary valve for explosion engines, an outer casing, a stationary inner casing formed with a plurality of ports and passageways communicating therewith, a water cooling chamber substantially surrounding the passageways merging into said ports, means for directing water into said chamber at its lowermost point, means for leading water from the uppermost point of said chamber whereby a correct circulation of cooling fluid is provided in said chamber, a rotating sleeve arranged between said inner casing and said outer casing, said rotating sleeve being formed with ports adapted to register at predetermined times with the ports of said inner casing, and anti-friction members for supporting said sleeve between said casings whereby the wear between the casings and the sleeve is reduced to a minimum. 40
11. In a rotary valve for explosion engines, an outer casing, an inner casing arranged in the outer casing and spaced there- 45

from, said inner casing being provided with an inlet passageway formed with a plurality of discharge branches for more evenly distributing the explosive mixture, an outlet 5 passageway extending for substantially the full length of said inner casing, a port from each of said passageways for each of the cylinders of said engine, and an inclined cooling chamber substantially surrounding all of 10 said passageways, and a rotary sleeve arranged in the space between said inner casing and said outer casing, said sleeve being

formed with ports adapted to register at different times with the ports in said inner casing for causing the proper intake and exhaust from and to said cylinders. 15

In testimony whereof I have signed my name to this specification in the presence of two subscribing witnesses.

MAX JAEGER.
